Inventor:
Rudolf Rath.

UNITED STATES PATENT OFFICE

2,026,706

SOLID WEB FOR ARTIFICIAL TOOTH
BACKING

Rudolf Rath, Munich, Germany

Application December 13, 1932, Serial No. 646,992
In Germany December 17, 1931

2 Claims. (CL 32—9)

It is known that single tooth-supports may be pressed by the dentist himself, using folded plate-strips, the ends of which are bent over. These turned ends, however, are too weak since they can be made only half the strength of a tooth-support's neck. The apparatus that have been constructed for this purpose so far are too expensive and, being dependent on the skill of the producer, they turn out products that differ in quality, i. e. they turn out unprecise products. First of all, however, the time required for the making of such single tooth-support is far too long, and when soldering the tooth-support to the backing, the solder—owing to the effect of capillarity—easily runs off along the gaps and between the two plate-strips of the tooth-support's neck, flooding thereby the tooth-support with solder and spoiling the whole work beyond repair.

It is known that part of these deficiencies may be overcome by using tooth-supports or bars that are massive and consist of a head and a neck, which latter widens conically at its bottom. If, now, the tooth-supports are not made each single support by itself, but if an elongated bar is formed, by division of which into sections the single supports are simply sliced off as may be desired, a time from 10 to 15 seconds is all that may be reckoned with for the making of one single support out of unformed metal. Such supports or bars may be made from melted metal by means of a moulding form, or from unformed raw metal, or from wire, or bars by means of a pressing form, or preferably by some drawing form, such as a drawing-plate or a forming roller. The great disadvantage however, is that supports consisting of a head and a neck having a conically widened end cannot be connected to the backing by either soldering nor by any other kind of method. On the contrary, a backing of melted metal has to be cast to the neck of the tooth-support. To that end a fire-proof matrice is needed, which has to be made anew all over again, each time it is to be used. Not to mention the fact that the cast metal is much less durable than the rolled variety, far too long a time is required for the making of the casting form, for the imbedding, drying, warming, glowing, and casting, all of which become necessary for but a single tooth, taking two hours or more.

The invention has for its object to produce a solid web or web bar partible into the bar lengths required and of such cross section that by adjusting and shifting by hand of the web made in the length required, or cut off from the web bar in the length required, in a slot made by means of a

fret-saw or slot tongs in a back plate, said slot extending from the edge of the plate, the back plate for the facette is obtained without any separate treatment or without the use of any special tool, the production of such a back plate by hand requiring at the utmost one to two minutes and the back plate and therefore also the facette standing accurately at right angles to the web. 5

With this object in view one or several longitudinal guide ledges are arranged at right angles to and on the neck of the solid web or of the solid web bar and at such height on the neck, which is extended at least by the thickness of the back plate, preferably however beyond the thickness, that, when bearing on one side or on both sides 10 against the back plate, the two correct distances of the web head from the back plate are determined and the vertical position of the web to the back plate is ensured. 15

Two embodiments of the invention are illustrated on a larger scale by way of example in the accompanying drawing, in which:—

Fig. 1 is a vertical section through a web bar alone,

Fig. 2 is a vertical section through the same web 20 bar inserted into a back plate,

Fig. 3 is a vertical section through another web bar alone,

Fig. 4 shows the web bar according to Fig. 3 inserted into a back plate. 30

In the form shown in Figs. 1 and 2, neck *b* of the web or web bar lying behind head *a*, which serves to receive the facette, has been provided at both sides of its back end with a protruding longitudinal guide ledge *c*, so that the neck of the web or web bar takes on the shape of a T. When the web or web bar is inserted into the backing *d*, which is provided with a slot at the edge, the two longitudinal ledges grip behind said backing. The inserting is done in a free-handed manner. The 35 web or web bar once inserted into the slotted backing, the backing is finished. 40

It only has to be soldered now. It may be seen by Fig. 2 that the backing is so securely fixed in its position by the bottom-piece *c* and the neck *b* 45 that any change of that position is quite impossible when the subsequent soldering takes place, which latter is done by hand and without any apparatus whatever.

In the form shown in Figs. 3 and 4, another 50 guide ledge *c'* has been provided, on each side of neck *b* and at right angles, in front of the pair of guide ledges at the back and at a distance which is, preferably, identical with the thickness of back plate *d*, and which guide ledge *c'*, contrary 55

to the laterally protruding ledges at the back, is receding. This is achieved by an arrangement which gives a smaller width to part *e* of the neck lying between both pairs of longitudinal guide ledges than to part *b* of the neck which lies before them. The back part of the neck is therefore of an I-shaped profile.

If the backing *d* provided with a slot is freely inserted into such support, as shown in Fig. 4, the backing is ready for use. Any soldering becomes unnecessary, for, as shown in Fig. 4, the backing is securely and unmovably clasped by two T-pieces: at the top, by the T-member of the neck, at the spot where its diameter begins to get thinner, and at the bottom, by the T-member forming the bottom-piece *c* on the neck.

Should the case require it, the two longitudinal guide ledges *c* may be employed alone too.

What I claim as new, and desire to secure by Letters Patent is:

1. An artificial tooth support comprising a backing having a slot therein whose sides are straight, a web bar having a shank of reduced area at its lower end fitted to the slot of the

backing, the said shank terminating in a ledge at right angles to the axis of the shank and bearing against the surface of the backing in which the shank is lodged, the reduced portion of the shank having a length equal to that of the thickness of the backing, and shoulders at right angles to the axis of the shank and at the upper portion of the reduced portion thereof fitting against the plane surface of the backing opposite that engaged by the ledge.

2. In a device of the kind described, the combination with a backing plate having a slot extending therethrough from one edge to a point spaced from the opposite edge, and a solid rail preformed to provide a head, a web and a base extending on both sides of the web, said web fitting the slot in the plate with the head spaced from the plate and the base fitting closely against the plate on the side opposite the head, the sides of said web being longitudinally grooved to fit closely on the portions of the plate at the sides of the slot.
